(57) CLAIM

The ornamental design of a longitudinally ribbed smoker's urn holder, as shown and described.

DESCRIPTION

FIG. 1 is a front perspective view of the longitudinally ribbed smoker's urn holder according to the inventive design;

FIG. 2 is a side elevation view of the inventive design as shown in FIG. 1, the view from the remaining sides and rear being the same as shown;

FIG. 3 is a top plan view thereof;

FIG. 4 is a bottom plan view thereof; and,

FIG. 5 is a longitudinal cross section taken along line 5—5 in FIG. 1.
